DETACHABLE EDGE FOR PLOWSHARES

William J. Drummond, Seattle, Wash.

Application March 12, 1936, Serial No. 68,517

6 Claims. (Cl. 97—125)

This invention relates to detachable edges for plow shares and particularly to those edges which are formed to provide flanges defining a relatively deep V-shaped recess along the upper edge of 5 the detachable edge member which receives the lower or forward edge of the share.

An object of my invention is to provide an edge of this character having resilient gripping tongues on one or more of the inner faces of the flanges, 10 which tongues extend toward the edge of the share when the detachable edge member is in place, the tongues accommodating themselves to the irregularities or inequalities on the face of the share and frictionally resisting any detachment 15 of the edge member.

Another object is to form the share with recesses preferably on the under face of the share and provide on a flange of the edge member spring tongues engaging the said recesses and acting in 20 the manner of pawls to prevent accidental detachment of the edge member from the share.

Other objects will appear in the course of the following description.

My invention is illustrated in the accompanying drawing wherein:

Figure 1 is a side elevation of a plow share with my improved edge member applied thereto;

Figure 2 is an enlarged section on the line 2—2 of Figure 1;

Figure 3 is a view of the edge member detached from the share and constructed as shown in Figures 1 and 2;

Figure 4 is a plan view of the form of edge shown in Figures 1, 2, and 3;

Figure 5 is a sectional view through the edge of a share and with a modified form of edge member applied thereto;

Figure 6 is a bottom plan view of the edge member shown in Figure 5, and a portion of the share 40 with which the edge member coacts;

Figure 7 is a fragmentary section through an edge member showing a metallic plate welded in place between the sections.

Referring to the drawing and particularly Figure 3, 10 designates an edge member adapted to be applied to a share A. This edge member is formed to provide at its rear end two spaced flanges 11 and 12 adapted to receive and fit over the edge of the share A. These flanges 11 and 12 are stamped 50 out to provide inwardly projecting resilient tongues 13, these tongues being directed at an angle to the forward edge of the edge member 10 and in the direction of the line of flow of the earth. The edge member 10 is capable of being 55 forced upon the forward edge of the share and

the tongues will accommodate themselves to any irregularities or inequalities in the opposite faces of the share and will bind frictionally upon the share so that the edge member, while detachably connected to the share, will be held firmly in place. 5

The structure shown in Figure 3 is particularly adapted for ordinary shares, but in Figures 5 and 6, I show a share A which is formed adjacent its edge with a series of recesses 14, these recesses being inclined upward and toward the forward 10 edge of the share and being preferably disposed upon the lower face of the share A. Coacting with this form of share is an edge member designated generally 15, which is also formed with opposed flanges 16 and 17, the lowermost flange 17 15 being formed with a series of spring tongues 18 stamped out from the flange and which are adapted to engage within the recesses 14 and which act in the manner of pawls snapping into place and preventing the accidental detachment 20 of the share. It will be seen from Figure 6 that the edge member 15, and this is also true of the edge member 10, has a form which is complementary to the form of the edge of the share so as to fit the outline of the edge of the share. 25

While an edge may be rolled in any conventional manner to provide the flanges 11 with the gripping tongues 13, for instance, or the gripping tongues 18, as shown in Figs. 5 and 6, the edge member may be manifestly formed in two 30 sections welded together, and if desired a thin strip of high carbon steel, as indicated in Fig. 7, may be disposed between the welded surfaces, this strip being designated 21, said strip extending out to the cutting edge 20. 35

Where an edge is placed upon an old share, that is, a share not formed with the recesses 14, then the gripping tongues 13, which may be as numerous as desired, will hold the edge in place frictionally and the more of these gripping 40 tongues there are provided, the better. Where, however, the share A is made with the recesses 14, as shown in Figures 5 and 6, it will not be necessary that there shall be as many recesses as there are tongues 18, as those tongues which are coincident with the recesses 14 will spring into position as shown in Figure 5, but those tongues on the edge member which are not coincident with any recess will simply bear frictionally against the surface of the share and increase the holding 50 power of the edge member on the share. 45

The edge, when once put on a share, should remain until worn out as it is unnecessary to sharpen the edges, because of the fact that these edges wear at top and bottom of the cutting edge 55

and thus being self-sharpening, but if it be desired to remove a worn edge, that is, an edge which has passed its usefulness, then the edge may be removed by springing the whole flange as, for instance, the lower flange 17 in Figure 5, off the share carrying the tongues out of the recesses 14. The whole edge is designed to have a spring temper.

What is claimed is:—

- 10 1. A plow share edge member having its rear portion formed to provide opposed spaced flanges adapted to embrace the cutting edge of a plow share, one of the flanges being formed with a plurality of inwardly projecting resilient tongues adapted 15 to contact with the share when the edge member is in place.
- 20 2. A plow share edge member having its rear portion formed to provide two flanges adapted to fit upon and embrace the forward edge of the plow share, each of said flanges being formed with a plurality of inwardly projecting resilient tongues adapted to frictionally engage the plow share and conform to the irregularities thereof.
- 25 3. The combination with a plow share having a forwardly and inwardly inclined recess in one of its faces, of an edge member therefor formed at its rear portion with opposed flanges defining a recess adapted to receive and embrace the edge of the plow share, one of said flanges having inwardly projecting portions adapted to engage in 30 said recesses.
- 30 4. The combination with a plow share having a plurality of upwardly and forwardly inclined

recesses in its lower face, of an edge member therefor, the rear portion of which is formed with two opposed flanges adapted to embrace and fit upon the forward edge of the share, the lowermost flange having upwardly and forwardly extending resilient tongues adapted to engage in said recesses.

5 5. An edge member for plow shares formed to provide two opposed flanges at its rear portion adapted to fit upon and embrace the edge of a plow share, the edge member being formed in two sections, an upper section and a lower section, the line of demarkation between said sections intersecting the lower end of the recess defined by said flanges, said sections being substantially 15 welded to each other, the weld including a hard metallic material which extends to the cutting edge of the edge member whereby as the softer portion of the edge wears off, the hard inner portion will be exposed.

20 6. An edge member for plow shares formed to provide two opposed flanges at its rear portion adapted to fit upon and embrace the edge of a plow share, the body of the edge member being formed in two sections, each of the sections including one of said flanges, a thin strip of high carbon steel disposed between the confronting surfaces of the two sections outward of the flanges and the two sections and the steel strip being 25 welded to each other, the strip extending to the 30 cutting edge of the edge member.

WILLIAM J. DRUMMOND.
